UNITED STATES PATENT OFFICE.

STEPHEN HORVÁTH, OF RACINE, WISCONSIN.

SPRING-HEEL CONSTRUCTION.

1,108,369.

Specification of Letters Patent.

Patented Aug. 25, 1914.

Application filed March 20, 1914. Serial No. 826,006.

To all whom it may concern:

Be it known that I, STEPHEN HORVÁTH, a citizen of the United States, residing at Racine, in the county of Racine and State 5 of Wisconsin, have invented certain new and useful Improvements in Spring-Heel Construction, of which the following is a specification.

This invention relates to certain new and 10 useful improvements in spring heel construction.

The primary object of this device is the provision of a plurality of resiliently-mounted hob nails in the heel of a boot or 15 shoe and so positioned for free use with all of the same excepting their contacting portions entirely hidden from view and protected from the elements.

A further object is to provide a resilient 20 hob nail structure having adjustable spring-tensioning devices and being of simple construction easily applied to a shoe as well as disassembled.

A still further object is to provide a shoe 25 heel constructed with a plurality of hob nail carrying sockets and having tension regulated spring-pressed nail members removably-mounted in said sockets.

With these general objects in view and 30 others that will appear as the nature of the invention is better understood, the same consists in the novel combination and arrangement of parts hereinafter fully described, illustrated in the accompanying drawings, 35 and pointed out in the appended claims.

In the drawings forming a part of this application and in which like designating characters refer to corresponding parts throughout the several views: Figure 1 is a 40 perspective view of a shoe employing the present hob nail construction, a portion of the heel being broken away. Fig. 2 is a vertical longitudinal central view taken through the heel portion of a shoe, and substantially upon line 2—2 of Fig. 3, and, Fig. 45 Fig. 3 is a bottom plan view of the shoe heel.

Referring more in detail to the drawings, the shoe 10 is illustrated with the present 50 form of improved heel secured thereto. For mounting the present structure firmly to the shoe, the heel portion 12 of the shoe sole is provided with a heel block 13 firmly affixed thereto and having a carrying plate 14 secured to the lower face thereof. A heel member 15 formed preferably of a single integral block, a wooden block being service-

able therefor, is provided with a plurality of bores 16 or transverse sockets bored therethrough and each adapted for the reception of a spring nail of the form hereinafter described. A screw 17 is centrally positioned within each bore and is screwed through both the plate 14 and firmly into the heel block 13, and thereby seats an annular disk 18 within the bore and firmly against the inner face of the plate 14, a screw driver being engageable with the screw from the open mouth of the bore and by means of the transverse kerf 19 of the screw. A helical spring 20 encircles the screw 17 and is secured to the outer face of the disk 18 before the insertion of the latter within the bore. The hob nail which is employed has a dome-shaped contacting face 21 and a disk-shaped base 22 while extending from the latter is a 60 threading tube 23 and by means of which the disk 22 is screwed upon the free outer end of the helical spring 20, and thereby maintains the disk and head in a resilient 65 sliding position within the bore and normally with the head 21 entirely projected therefrom.

From the above detailed description of the manner of assembling the present spring 70 hob nail heel structure, the entire operation 85 of the device will be clear. With the elements assembled as illustrated, any pressure exerted upon the projected heads 21 as in the act of walking, allows the heads to resiliently slide inwardly and in effect produces 90 not only a spring calk for the heel but also a resilient spring mounting for the heel portion of the shoe, the separate cushioning members being advantageous in traveling over a rough road-bed. The tension of the 95 springs 20 upon the nail head or calks may be regulated by turning the heads 21 inwardly or outwardly upon said springs as may be desired.

While the forms of the invention herein 100 shown and described are what are believed to be preferable embodiments thereof, it is nevertheless to be understood that various forms and modifications thereof may be had without departing from the spirit and scope 105 of the invention as claimed.

What I claim as new and desire to secure by Letters Patent is:—

1. A device of the class described comprising a shoe heel having a vertical bore therein, a disk seated upon the top of said bore, a screw within said bore extending through 110

said disk and engaging the heel, a helical spring encircling said screw and secured to said disk, and a head normally projecting from said bore and having a threaded ex-
5 tension engaging the outer free end of said spring.

2. In a combination with a shoe having a heel block, a heel member and an intermediate plate secured to said block, said heel member provided with socket bores opening at the tread portion of the heel member, disks seated within said bores, screws centrally positioned in said bores and extending through said disks and engaging said 15 plate and heel block, helical springs encircling said screws and secured to said disks, and head members mounted upon the free ends of said springs and normally partially projected from the open ends of said bores.
20 3. A heel structure comprising a block se-

cured to a shoe and having a plurality of inwardly-extending open sockets extended therethrough, disks within said sockets, securing screws extending through said disk and engaging the shoe, helical springs 25 encircling said screws and secured to said disks, head disks slidably-mounted within the outer ends of said bores, threaded collars inwardly carried by said head disks and adjustably receiving the free ends of said 30 springs, and dome-shaped heads carried by said head disks and normally projected exteriorly of said bores and extending from the tread surface of the heel.

In testimony whereof I affix my signature 35 in presence of two witnesses.

STEPHEN HORVÁTH.
